Term of patent 7 years

(Cl. D29—20)

To all whom it may concern:

Be it known that I, Andrew G. Giegold, Jr., a citizen of the United States, residing at Mount Vernon, in the county of Westchester and State of New York, have invented a new, original, and ornamental Design for a Picture Holder or Similar Article, of which the following is a specification, reference being had to the accompanying drawing, forming part thereof.

The figure is a perspective view of a picture holder or similar article, showing my new design.

The essential features of my design reside in a picture frame of the configuration shown in the drawing having as side brackets slotted letters of the alphabet. It is understood that the letters "C" and "B" are illustrative only and that other letters of the alphabet embodying the design of the letters shown in my Patent D. 146,430 of March 4, 1947, may be employed.

I claim:

The ornamental design for a picture holder or similar article, as shown and described.

ANDREW G. GIEGOLD, JR.
